UNITED STATES PATENT OFFICE.

CHESTER C. CARTER, OF PERRYTON, TEXAS.

PUMP.

Application filed January 20, 1923. Serial No. 613,974.

To all whom it may concern:

Be it known that I, CHESTER C. CARTER, a citizen of the United States, residing at Perryton, in the county of Ochiltree and State of Texas, have invented new and useful Improvements in Pumps, of which the following is a specification.

This invention relates to pumps and contemplates a structure designed for use in deep wells, and one wherein the use of leather plungers and sucker rods is dispensed with.

The nature and advantages of the invention will be better understood when the following detailed description, is read in connection with the accompanying drawings, the invention residing in the construction, combination and arrangement of parts as claimed.

20 In the drawings forming part of this application, like numerals of reference indicate similar parts in the several views, and wherein:

25 Figure 1 is a vertical sectional view through the pump.

Figure 2 is a fragmentary view showing the inner cylinder on its up stroke.

30 Figure 3 is a sectional view taken on the line 3—3 of Figure 1.

Figure 4 is a view of the pump in elevation.

Referring to the drawings in detail, 10 indicates the outer cylinder of the pump which rests upon the ground in the bottom of the well.

Arranged in the lower end of this cylinder is a valve cage 11, in which a ball valve 12 operates, the valve normally engaging its seat 13. This cylinder is coupled as at 40 14 to a perforated section 16, the water entering the pump through the perforations of this section as will be readily understood.

45 Arranged to slide within the outer cylinder 10, is an inner cylinder 17, the latter being fitted to a nicely within the outer cylinder and operating through a packing gland 18 as illustrated. Threaded into the upper end of the inner cylinder 17 is a plug or a tubular member 19 having a central bore to receive a discharge pipe 20 which is considerably smaller in diameter than the cylinder 17. Communicating with and projecting from the pipe 20 is a discharge spout 21. Arranged within the cylinder 17 adjacent the lower end thereof is a

valve cage 23, to limit the movements of a ball valve 24 which normally engages its seat 25. The valve cages 11 and 23 respectively, each include a threaded collar 28 having threaded engagement with the upper end of each of the cages 11 and 23. A transverse pin 29 is carried by each of the collars and serves to limit the upward movement of the ball valves 12 and 24 respectively. These pins in addition to constituting stops for the ball valves above mentioned serve as handles whereby the collars may be threadedly engaged with the cages or removed therefrom. The inner 70 cylinder 17 and the discharge pipe 20 reciprocates as a unit within the outer cylinder 10, whereupon the water is lifted with a minimum of power and discharged through the spout 21. On the up stroke 75 of the inner cylinder 17, the ball valve in the lower end of the outer cylinder is lifted as clearly shown in Figure 2, thereby admitting the water from the perforated section 16 to the outer cylinder 10. During 80 the upper stroke of the inner cylinder, a ball valve 23 thereof retains its seat, but on the down stroke of this cylinder 17, the valve is opened to admit water from the outer cylinder 10 into the inner cylinder 17. 85 As the inner cylinder 17 is moved downwardly, the valve in the outer cylinder closes, any source of power may be utilized to reciprocate the inner cylinder 17, and for this purpose an operating rod 26 is 90 coupled to the upper end of the pipe 19. This rod 26 is associated with a shaft 27 which may be rotated by a wind mill or any other source of power.

While it is believed that from the foregoing description, the nature and advantages of the invention will be readily apparent, I desire to have it understood that I do not limit myself to what is herein shown and described and that such changes 100 may be resorted to when desired as fall within the scope of what is claimed.

Having thus described the invention, I claim:

A pump of the character described comprising a stationary cylinder including a perforated section depending from the lower end thereof, a valve seat and cage threaded in the cylinder above the perforated section, a ball valve arranged with 105 in the cage and normally engaging said seat, a second cylinder arranged to slide

within the stationary cylinder, a valve seat and cage threaded in the lower end of the second cylinder, a ball valve normally engaging said seat, a collar arranged in each of said cylinders, a transverse pin carried by each collar and adapted to limit the upward movement of the adjacent ball valve, a discharge pipe rising from the upper end of the second cylinder and including a laterally disposed branch, a shaft mounted

for rotation, a reciprocating rod actuated by said shaft and connected with the discharge spout, whereby rectilinear movement is imparted to said pipe, and said valve alternately opened and closed, and ¹⁵ means for rotating said shaft.

In testimony whereof I affix my signature.

CHESTER C. CARTER.
